United States Patent Office

Des. 178,471
Patented Aug. 7, 1956

178,471

CARPORT OR SIMILAR ARTICLE

Charles E. Volk, Great Falls, Mont.

Application November 26, 1954, Serial No. 33,252

Term of patent 14 years

(Cl. D13—1)

FIG. 1

FIG. 2

FIG. 3

FIG. 4

Figure 1 is a perspective view of a carport or similar article embodying my new design;

Figure 2 is a side elevational view thereof;

Figure 3 is an end elevational view thereof; and

Figure 4 is a top plan view thereof.

The dominant characteristics of my new design are shown in the full lines of the drawing.

I claim:

The ornamental design for a carport or similar article, as shown and described.
